UNITED STATES PATENT OFFICE.

S. H. WHITAKER, OF CINCINNATI, OHIO.

NUT-MACHINE.

Specification of Letters Patent No. 18,259, dated September 22, 1857.

To all whom it may concern:

Be it known that I, SAMUEL H. WHITAKER, of Cincinnati, Hamilton county, Ohio, have invented new and useful Improvements in Nut-Machines; and I hereby declare the following to be a full and exact description thereof, reference being had to the accompanying drawings, making part of this specification.

10 The nature and object of my invention consist in a provision for making metallic nuts of definite thickness not materially varying from that of the bar, and so as to save the scrap produced by punching.

15 In the accompanying drawings—Figure 1 is a side elevation of a machine illustrating my invention, taken at the period of the commencement of the operation of clamping. Fig. 2 is a horizontal section at the line $\alpha\alpha$

20 Fig. 1, taken at the period when the preparatory punching is completed. Fig. 3 is a vertical section at the line $\alpha\alpha$, Fig. 2. Fig. 4 is a horizontal section in the same plane as Fig. 2; but taken at that stage of 25 the operation when the bar is forwarded for the separation and completion of the nut. Fig. 5 is a vertical section at the line $\alpha\alpha$, Fig. 4, taken at the period of the completion and liberation of the nut.

30 A, is the frame which supports the various operating parts.

Cams D, P, G, G', on the shaft B, impart by their rotation the proper motives to the punching, shearing and pressing mechanism.

35 I employ a system of preparatory and finishing dies having the customary central apertures for the punches.

The dies N, and L are mounted on and 40 advance and recede together with a stock F, which has a longitudinal sliding motion imparted to it by the cam D. The die N is provided with upper and lower flanges or lugs $n. n.$ distant from each other the width of the bar. The central aperture of

45 the die N, is occupied by a punch b , (called by me the preparatory punch) which has an independent sliding motion imparted to it by the cam P, which acts on the stock p , of said punch.

50 The die L is provided with a cutting edge l , which separates the partially formed nut.

The counter die K, is retracted by a brace of cams G, G', working in yokes H, H', 55 which proceed from the crosshead I, attached to the stock of the counter die.

A punch J, being firmly fixed in the frame occupies the central aperture of the counter die K, the latter sliding to and fro on the punch.

60 R, R', are adjustable stops for determining definitely the range of the cross-head I.

The punch J, and attachments h , h' , of the cross-head have a longitudinal adjustment by means of screws as represented.

65 C, C', C'', are a suit of rolls employed for shaping the nut and similar in principle to those described in my patent of June 9th, 1857. In the present case, however, they are so arranged in relation to the dies that 70 the greatest amount of pressure of the dies takes place after the nut has once passed between the rolls and previous to its re-passing under their action.

75 O, is the aperture through which the bar is fed to the machine.

The operation is as follows: The parts being in the relative positions indicated in Fig. 1 and a bar having been fed in until its end touches the side of the die L, the stock F, moving forward (by the rotation of the cam D.) clamps first the upper and lower edges and then the flat of the bar. The end of the bar being thus clamped on all sides, a quick movement imparted to the 85 punch by the cam P, causes it to penetrate nearly the entire thickness of the bar. The portion of the bar about to be separated for a nut is thus punched nearly through its substance, but is not increased in width 90 or thickness because held on one side and both edges by the die N, on the other side by the wall of the feed aperture and at the end by the side of the die L. The metal thus displaced from the center by the preparatory punch becomes incorporated in the 95 substance of the bar or blank but—as the latter is confined on every side but that toward the feed aperture—no change occurs in the dimensions of the blank, the result being simply an increase in the length of the bar by an amount of metal, equal to that displaced by the punch. This being 100 accomplished, the punch b , and die stock F, being now released by the continued rotation of the cams, are retracted by a spring, or otherwise and the bar is fed forward until its end touches a suitable stop R'.

105 With the next advance of the stock F, the cutting edge l , of the die L, severs the blank from the bar and the next space on the bar undergoes preparatory punching, while the

separated portion is carried forward through and beyond the suit of rolls C, C', C'', until the cross-head I, arriving at the extent of its motion, the blank is forcibly compressed between the die and counter die and becomes slightly flattened thereby, so that on returning through the rolls it is subjected to a second pressing and by this means the corners are filled out and the nut 10 perfectly formed. The form of the cam D, limits the retraction of the die stock F. to the required speed until the completion of the final pressing of the nut, at which time (being released) the stock and dies 15 F N L, fall back to their starting point as before explained, resulting in the release of the completed nut. The thin wad punched from the nut in its first passage through the rolls, escapes through the passage 20 sage t.

I claim as new and of my invention herein:

The use of the preparatory punch b, and die N, in the described combination with the shearing and finishing die L, punch or 25 mandrel J, and counter die K, whereby a nut of definite thickness is formed by first partially punching the blank while joined to the bar, and confined on every other side, then separating the blank and completing 30 the punching and shaping; the whole being constructed and operating substantially in the manner herein set forth.

In testimony of which I hereunto set my hand.

S. H. WHITAKER.
